UNITED STATES PATENT OFFICE

RAYMOND L. PLUMLEY, OF BROOKLYN, NEW YORK, ASSIGNOR TO FREDERICK OSANN COMPANY, OF NEW YORK, N. Y., A CORPORATION OF NEW YORK

CLUTCH MECHANISM

Original application filed May 19, 1927, Serial No. 192,698. Divided and this application filed August 2, 1929. Serial No. 382,861.

The general object of my present invention is to provide an improved clutch mechanism adapted for use in imparting successive angular movements in the same direction to a rotatable part, and primarily devised for use in intermittently rotating the feed disc of an overseaming sewing machine capable of operation at relatively high speeds. My improved clutch mechanism is characterized by its mechanical reliability and the effectiveness for the use specified and for analogous purposes. The various features of novelty which characterize my invention are pointed out with particularity in the claims annexed to and forming a part of this specification. For a better understanding of the invention, however, and the advantages possessed by it reference should be had to the accompanying drawing and descriptive matter in which I have illustrated and described a preferred embodiment of the invention.

Of the drawing:—

Fig. 1 is an elevation in section;

Fig. 2 is an elevation taken similarly to Fig. 1 but on a larger scale and partly broken away, and showing a portion only of the apparatus shown in Fig. 1;

Fig. 3 is a section on the broken line 3—3 of Fig. 2; and

Fig. 4 is an elevation of a portion of the clutch actuating means, with parts broken away and in section on the line 4—4 of Fig. 1.

In the accompanying drawing I have illustrated the use of the present invention in a sewing machine for overseaming shown and described herein in part only but more fully disclosed in, and the novel features of which are claimed in, my prior application Serial No. 192,698, filed May 19, 1927, of which the present application is a division.

The sewing machine shown in part by the drawing herein, comprises a vertical feed shaft B journalled in upper and lower bearings A⁴ and A⁵ formed in the machine housing A. The shaft B carries a feed disc C at its upper end which is intermittently rotated as hereinafter described, so that in contact with a second feed disc C' frictionally driven by the disc C, the work gripped between the two feed discs will be intermittent

ly advanced in proper timed relation with the reciprocating movements imparted to the needle I², and the reciprocating and oscillating movements imparted to the looper M. The needle I² and looper M are given their movements by the main shaft H of the sewing machine through means which need not be described herein, as they form no part of the present invention, and are fully disclosed in my said prior application.

Secured to the shaft B is a gear B², the peripheral teeth of which are in mesh with the teeth of a crown gear D secured to a horizontal shaft D' suitably journalled in the machine housing. Preferably the teeth on the gears B² and D are of such character that when the gear D is rotated in the counter-clockwise direction as seen in Figs. 1 and 2, the feed disc C is rotated in the work advancing rotation, but the gear B² is incapable of rotating the gear D in either direction. To this end the gears B² and D may be identical with the similarly designated gears of my prior Patent No. 897,846.

The gear D is given intermittent rotative movements in the counter-clockwise direction by an oscillating actuating lever E and associated novel clutch provisions, now to be described, by means of which the lever E is locked to the gear D when the lever E is turned in the counter-clockwise direction as seen in Fig. 1, and is released from the gear D when turned in the opposite direction. The lever E is formed with an aperture E' through which the shaft D' passes. The aperture E' is elongated in a direction transverse to the length of the lever E to permit some corresponding transverse play of the lever relative to the shaft D'. Associated with the lever E are two clutch parts ea' and ea² arranged one below the other above the lever. Each of the two clutch parts is formed at its opposite ends with spaced apart cylindrical bearing surfaces e³ which fit against the inner wall of a cylindrical flange D⁴ formed at the front side of the gear D, as viewed in Figs. 1 and 2.

The lever E is formed with cam-like projecting portions E² and E³ at its lower and upper sides, respectively, which engage bear-

ing surfaces formed on the members ea' and ea^2 , respectively. The cam portions E^2 and E^3 are diametrically opposed to one another, the cam E^2 being to the left and the cam E^3 to the right of a vertical plane including the axis of the gear D and transverse to the length of the members ea' and ea^2 . A compression spring e^5 acts between the lever E and the right end of the member ea' as seen in Fig. 2, and a similar compression spring e^5 acts between the other end of the member ea^2 and the lever E . A spring e^4 acts between the left hand end of the part ea' , as seen in Fig. 2, and a lug or finger e' carried by the lever E , in a direction tending to turn the member ea' about the axis of the gear D in the clockwise direction when the lever E is turned in the clockwise direction, and a similar spring e^4 acts similarly between the right hand end of the member ea^2 and a lug or shoulder e^2 carried by the lever E . As shown, the lugs e' and e^2 are integral portions of a part e rigidly secured to the member E .

When force is applied to the outer end of the lever member E to turn the latter in the counter-clockwise direction, the cam portions E^2 and E^3 tend to spread the members ea' and ea^2 apart and this creates a frictional engagement between the surfaces e^3 of the members ea' and ea^2 and the inner wall of the flange D^4 which prevents movement of the members ea' and ea^2 relative to the gear D . The lever member E is thus locked to the gear D so that the latter shares the counter-clockwise turning movement of the lever E . The springs e^5 contribute to the operation just described by normally holding the corresponding ends of the members ea' and ea^2 snugly in contact with the flange D^4 so that there is practically no lost motion to be overcome when the initial spreading apart of the members ea' and ea^2 occurs. When the movement of the lever E is reversed, the cam portions E^2 and E^3 cease to press the members ea' and ea^2 apart, and the springs e^4 and e^5 , acting on the ends of the members ea' and ea^2 , then cause the latter to turn about the axis of the member D with the lever E . As shown, the lever E is formed with a slot or groove F^5 in its rear side loosely receiving the flange D^4 , but there is no operative engagement of the walls of the slot with the flange.

As a safeguard against any tendency of the gear D to rotate in the clockwise direction, as a result of lost motion or otherwise, I advantageously provide a suitable locking device or brake. This, as shown, is in the form of a bar eb formed with a slot or groove e^{10} in one side which receives the flange D^4 . The outer end of the bar eb bears against a stop A^{11} carried by the machine housing and a spring e^{11} tends to hold the brake in the position shown in Figs. 1 and 2 in which the walls of the slot or groove e^{10} engage the inner and

outer walls of the flange D^4 so as to positively hold the gear D against rotation in the clockwise direction. The spring e^{11} yields to permit the slight turning movement of the bar eb necessary to permit the flange D^4 to move freely in the slot or groove e^{10} , when the gear D is rotating in the counter-clockwise direction.

The outer end of the member E is connected by a pivot pin E^6 to a lever F . The lever F is pivotally connected to the housing A through a fulcrum part F' passing through a longitudinal slot F^2 in the lever F , and having a threaded extension which passes through a horizontal slot A^8 in the housing A and may be clamped in any desired position in said slot by a nut F^3 . The end of the lever F opposite to that connected to the member E is pivotally connected by a pivot pin G' to a link G , the upper end of which forms an eccentric strap portion G^{12} surrounding an eccentric disc H' secured to the main driving shaft H of the sewing machine.

The invention possesses various advantages, and in particular is characterized by its effectiveness and by its positive action and the avoidance of lost motion or overtravel in the operation of the gear D at relatively high speeds.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent is:—

1. A shaft and means for giving repeated angular movements in the same direction to said shaft comprising a member carried by the shaft and provided with a hollow cylindrical portion coaxial with the shaft, a pair of segmental parts located on opposite sides of the axis of said shaft and engaging the inner surface of said cylindrical portion, a lever loosely mounted on said shaft with capacity for lost motion relative to the shaft in a direction toward and away from said parts, and means carried by said lever engaging, and tending to spread apart said segmental parts when the lever is turned in one direction, said parts having a limited movement of approach when the lever is turned in the opposite direction.

2. A shaft and means for giving repeated angular movements in the same direction to said shaft comprising a member carried by the shaft and provided with a hollow cylindrical portion coaxial with the shaft, a pair

of segmental parts located on opposite sides of the axis of said shaft and engaging the inner surface of said cylindrical portion, a lever loosely mounted on said shaft with capacity for lost motion relative to the shaft in a direction toward and away from said parts, means carried by said lever engaging, and tending to spread apart said segmental parts when the lever is turned in one direction, said parts having a limited movement of approach when the lever is turned in the opposite direction, and resilient means acting between said lever and said parts and tending at all times to spread said members apart, and tending to cause said parts to move angularly with said lever when the latter is turned in said opposite direction.

3. In a sewing machine work feed, the combination with a shaft, of means for giving successive angular movements in the same direction to said shaft comprising a gear carried by said shaft and having a hollow cylindrical portion coaxial therewith, a pair of segmental clutch parts located on opposite sides of the axis of said shaft and arranged to fit against the inner surface of said cylindrical portion, an actuating lever loosely mounted on said shaft and capable of lost motion relative thereto in a direction toward and away from said clutch parts, spring members arranged between said lever and said clutch parts and holding said clutch parts at all times in contact with said cylindrical portion, cam means carried by said lever arranged to engage and spread apart said clutch parts when said lever is turned in one direction, and other spring members arranged between said lever and said clutch parts causing said clutch parts to move angularly with said lever relative to said cylindrical portion when said lever is turned in the opposite direction.

Signed at Brooklyn, in the county of Kings and State of New York this 31st day of July, 1929.

RAYMOND L. PLUMLEY.
